(57) **CLAIM**

The ornamental design for a cardbus wire adapter, as shown and described.

DESCRIPTION

FIG. 1 is a perspective view of a cardbus wire adapter showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
